DESIGN FOR A REFLECTOR FOR TUBULAR LAMPS

John A. Hoeveler, Mount Lebanon, Pa., assignor to
Pittsburgh Reflector Company, Pittsburgh, Pa.,
a corporation of New Jersey

Application September 20, 1941, Serial No. 103,434

Term of patent 14 years

To all whom it may concern:

Be it known that I, John A. Hoeveler, a citizen of the United States, residing at Mount Lebanon, in the county of Allegheny and State of Pennsylvania, have invented a new, original, and ornamental Design for a Reflector for Tubular Lamp, of which the following is a specification, reference being had to the accompanying drawing, forming part hereof.

In the drawing,

Figure 1 is a perspective view from below of a

reflector for tubular lamp showing my new design;

Figure 2 is a transverse sectional view thereof;

Figure 3 is a partial side elevation thereof; and

Figure 4 is a partial longitudinal section taken along the plane of line IV—IV of Figure 2.

I claim:

The ornamental design for a reflector for tubular lamp, as shown.

JOHN A. HOEVELER.
